SUBSEQUENT TREATMENT

Royal Little, Providence, R. I., assignor to Franklin Rayon Corporation, Providence, R. I., a corporation of Rhode Island

Application October 29, 1936, Serial No. 108,234

14 Claims. (Cl. 8—155)

This invention relates to a method and apparatus for preparing batches of textile packages for subsequent processing treatment or a series of treatments such as washing, dyeing, drying, 5 reconditioning and the like.

One of the objects of the present invention is to provide a method and apparatus for expediting the assembling of groups of textile packages on supporting holders to form self-contained 10 units.

Another object of the invention is to provide a method and apparatus by which the several steps of assembling the packages on their holders are performed at different stations while the 15 holders are supported in a substantially horizontal plane to divide the labor and prevent fatigue on the part of the operators.

Another object of the invention is to provide a method and apparatus for coordinating the assembly of the groups of packages into self-contained units and the mounting of the units on a portable processing carrier to simplify the handling of the packages and to generally increase 20 the efficiency of the operations.

Another object of the invention is to provide an apparatus of the type indicated including an assembly turntable and a carrier-supporting turntable arranged in adjacent relationship and adapted to be rotated to position the assembled 25 package units opposite that portion of the carrier on which the units are to be mounted.

Another object of the invention is to provide an apparatus of the type indicated which is of simple and compact design, sturdy and rugged 30 construction, and capable of use over long periods of time without requiring repair or replacement of its parts.

Further objects of the invention are set forth in the following specification which describes a 35 preferred form of construction of the apparatus, by way of example, as illustrated by the accompanying drawings. In the drawings:

Fig. 1 is a plan view of the apparatus indicating the progress of the package-assembling operations at the different stations on one of the turntables and the relation of the assembled package units with respect to the carrier supported on the other turntable;

Fig. 2 is an enlarged side elevational view of 40 the assembly turntable viewed in the direction indicated by the arrow in Fig. 1 and showing the means for rotating the turntable between successive stations; and

Fig. 3 is a longitudinal sectional view taken 45 on line 3—3 of Fig. 1 showing the carrier for the

package units mounted on its turntable in a pit below the floor on which the assembly turntable is supported.

In the assembling method heretofore used the 5 holders are held in an upright position and a group of the textile packages applied thereto by sliding them over the end of the holders. With this method it is necessary to hold each package in the hand as it is lowered on the holder to prevent damage to the yarn or deformation of the package. As the holders are of considerable 10 length the operator must constantly stoop or bend over to lower the packages into position, and this results in loss of time while causing considerable 15 fatigue. After a group of the packages have been assembled, an end plate or cap is attached to the holder to lock the packages in position and form a self contained unit. When assembled the 20 units are carried to a kier and lowered into position to mount them therein. If the kier is located in a pit, it is necessary for the operator to bend over again to mount the units therein, thus entailing considerable physical effort and increasing the fatigue of the operator. Due to the 25 unnatural position in which the package unit must be held to mount it in the kier considerable difficulty is experienced and time wasted in alining the end of the unit with its supporting means in the kier.

In accordance with the present method the 30 holders are first mounted on a turntable in either a substantially horizontal plane or slightly inclined upwardly from the horizontal. The turntable is then rotated to another station where the individual packages are applied over the 35 extended ends of the holders with spacers therebetween. Due to the substantially horizontal position of the holders an operator may apply the packages and spacers thereto while either standing or sitting in an upright position. Further, with the present method of assembly each 40 package applied pushes the ones ahead along the holder without damage to the yarn or deformation of the packages. Less physical effort is required and both hands may be used in applying 45 the packages which results in a considerable saving of time in the assembling operation. When all of the several package holders located at the assembling station have been loaded the turntable is again rotated to move the assembled 50 packages to another station. At this station the caps are applied to the ends of the holders to hold the packages in position thereon, thereby forming self-contained units or stacks. The turntable is then again rotated to transfer the 55

package units to a final station in the assembling operation where the units are removed for transfer to the processing apparatus.

Instead of transferring the package units directly to the kier the present invention contemplates the use of a portable carrier of the type illustrated and described in a prior pending application, Serial No. 56,338, filed December 27, 1935, now Patent Number 2,125,937, dated August 9, 1938. The carrier is preferably of hollow or chambered construction having an opening for cooperation with an inlet pipe for a treating fluid and means for supporting the package units. In accordance with the present method the portable carrier is lowered into a pit closely adjacent the assembly turntable and rotatably supported on its own turntable. The carrier is thus positioned at the side of the assembly turntable where the package units are removed so that they may be quickly transferred to the carrier by merely lowering them into position thereon. The carrier supporting turntable is rotatable to position its unit-supporting means directly below the assembly turntable to avoid the necessity of carrying the package units around the carrier. A hinged platform is preferably provided over the pit in which the carrier is located so that an operator may stand directly above the supporting means on which the package units are to be lowered.

Referring to the present drawings, the apparatus on which the packages are first assembled comprises a standard or pedestal 4 and a turntable 5 rotatably mounted thereon. The pedestal 4 may be of any suitable construction being herein illustrated as a framework comprising angle-iron legs 6 and cross-struts 7 with a bearing plate 8 at the top. A vertical shaft or spindle 9 extends upwardly from the pedestal 4, being supported on one of the cross-struts 7 at its lower end and by the bearing plate 8 through which it projects. The bearing plate 8 has an upwardly projecting boss 10 surrounding the shaft 9 with its upper face forming an annular seat 11. The turntable 5, which may be of any suitable form, is herein illustrated as a hollow casting in the shape of the frustum of a pyramid to provide inclined sides 12 with a bottom plate 13 fixed thereto. The turntable 5 is mounted to rotate about the shaft 9 and is supported on the annular seat 11 of the boss 10 with an anti-friction ball bearing 14 therebetween. Upper and lower flanged bearings 16 forming journals for the shaft 9 are attached to the turntable by means of bolts 21 extending through their flanges. A collar 15 on the upper end of the shaft 9 holds the turntable 5 against movement longitudinally of the shaft 9.

Suitable means are provided on the turntable 5 for supporting package-holders H. As herein illustrated, the supporting means take the form of spindles 17 which project outwardly from the inclined sides 12 of the turntable 5 at right-angles thereto; the holders H being preferably in the form of hollow perforated tubes which fit over the spindles. The spindles 17 are shown as inclined upwardly with respect to a horizontal plane for the purpose of retaining the packages on the holders H before the end caps are applied thereto, but it is to be understood that they may be arranged horizontally within the scope of the present invention. The spindles 17 are preferably formed with threaded ends screwed into the inclined sides 12 of the turntable 5. Notched rings 19 are provided at the inner attached ends

of the spindles for cooperation with correspondingly notched bases 18 on the holders H to be later described. As herein illustrated, three tiers of spindles are provided on the turntable 5, the two lower tiers comprising five spindles each and the upper tier having four spindles due to the reduced width of the inclined sides 12 adjacent their upper edges. If desired, however, the turntable may carry a greater or lesser number of spindles.

A beveled ring-gear 20 is formed on or attached to the flange of the lower bearing 16 of the turntable 5 concentrically of its axis. A beveled pinion-gear 22 cooperates with the teeth of the gear 20 to rotate the turntable 5 to a plurality of operative positions, the ratio of the gear and pinion being preferably such that the turntable is rotated through one quarter of a revolution at each rotation of the pinion 22. The pinion 22 is fixedly secured to the end of a crank-shaft 23 mounted in a pair of bearings 24 on the top plate 8 of the pedestal 4 and a bearing 25 at the upper end of an outboard stanchion 26. The crank-shaft 23 thus extends outwardly from the turntable beyond the ends of the spindles 17 and carries a crank 27 fixed to its outer end to render its handle 28 accessible to the operator. Suitable latching means are provided in the handle 28 for automatically locking the crank-shaft 23 from turning after each complete revolution. As herein illustrated the handle 28 is formed with a reduced extension or plunger-pin 29 rotatably and slidably mounted in the hub at the end of the crank 27. The plunger-pin 29 projects beyond the hub to adapt it to cooperate with a recess 30 in the stanchion 26 and a spring 31 in the hub normally tends to press the plunger-pin into the recess. The plunger-pin 29 may be withdrawn from the recess by moving the handle 28 outwardly away from the stanchion 26 to permit the crank 27 and shaft 23 to be rotated. For convenience of illustration, the operating crank 27 for the assembly turntable 5 is shown as located at the station designated B, but it may be located in any convenient position as, for example, between stations or at a point adjacent the carrier turntable-operating means so that one man may operate both turntables.

As illustrated in Figs. 1 and 3, the carrier turntable 35 is located adjacent the assembly turntable 5, being preferably mounted in a pit 36 below the floor on which the pedestal 4 of the assembly turntable is supported. The turntable 35 is mounted on a ribbed base-plate 37 having a circular track 38 at its outer periphery and a hub 39 at its center. A stud-shaft 40 is fixedly mounted in the hub 39 and has a radial flange 41 intermediate its ends which seats on the upper face of the hub. The turntable 35 comprises a circular plate 42 with a central hub 43 and a marginal upstanding flange 44 at its outer edge. Ribs 45 formed integrally with the plate 42 extend radially outwardly from the hub 43 to stiffen and reinforce the structure, being provided with upwardly-extending tapered portions adjacent the hub which serve as a centering guide for a purpose to be later explained. The turntable 35 is rotatably mounted on the stud-shaft 40 which extends upwardly through a bushing 46 in the hub 43, the hub being supported on the flange 41 with a ball thrust-bearing 47 therebetween. A plurality of wheels or rollers 48 are journaled on casters 49 depending from the plate 42 of the turntable 35 to adapt them to roll on the track 38 of the base-plate 37.

The turntable 35 is rotated by an endless belt 50 which extends around a sheave 51 on the flange 44 of the plate 42 and a driving pulley 52. The pulley 52 is carried by and fixed to a gear 53 journaled on a shaft 54 rigidly held in an adjustable bracket or support 55 which is mounted to slide in ways 56 on a bed-plate 57. The pulley 52 is adapted to be rotated from a manually-operable shaft 60 carrying a pinion 59 fixed to its lower end and meshing with an idler gear 61 which meshes with the gear 53. The shaft 60 extends upwardly through a fixed cover or floor 62 extending across the top of the pit 36 and having a circular opening 76 above the turntable 35. The shaft 60 is journaled in a bearing 63 bolted to the cover 62 and a handwheel 64 fast on the upper end of the shaft provides for manually turning the latter to cause the turntable 35 to be rotated in the same direction. The movable support 55 which carries the above-described gearing may be adjusted toward and away from the turntable to properly tension the belt 50 by means of a threaded stud 65 fastened to the support with a nut 66 at its end which cooperates with a fixed abutment or lug 67 on the bed-plate 57.

The turntable 35 is adapted to support a hollow carrier 70 of the type illustrated and described in a prior pending application, Serial No. 56,338, referred to above. Suffice it to state herein that the carrier 70 has an upstanding tubular post 71 with a bail 72 at its upper end to adapt it to be lowered into and lifted out of a kier or other vessel. The carrier has a circular opening 73 in its bottom wall for cooperation with the inlet pipe of the kier or other container to admit a treating fluid to its interior. Its upper flat wall has a series of nipples 74 communicating with its interior and provided with guides 75 projecting upwardly therefrom, see Fig. 3. The carrier 70 may be lowered into the pit 36 through the circular opening 76 in the cover 62 by any suitable means, such as a chain-tackle, electric hoist or the like, and is centered on the turntable 35 by the edges of the tapered portions of the ribs 45 on the hub 43 entering the opening 73 in the bottom of the carrier. The carrier 70 is supported with its outer rim resting on the upper edge of the upstanding flange 44 on the turn-table 35.

Hinged to one side of the opening 76 in the cover 62 adjacent the assembly turntable 5 is a relatively narrow plank or platform 78 which normally extends inwardly toward the center of the carrier 70 to provide a support for the operator. The platform 78 is bifurcated at its end to straddle the post 71 of the carrier 70 and is adapted to be supported in horizontal position by suitable wheels or casters 79 on its under side which rest on the top of the carrier 70. The platform 78 is spaced above the top of the carrier 70 a sufficient distance to permit the upstanding guides 75 to pass thereunder when the turntable 35 is rotated while its hinges permit it to be swung back to inoperative position in the manner indicated by the dash lines in Fig. 3. The apparatus having now been described as embodied in a preferred form of construction, its mode of operation will next be explained.

With the parts of the apparatus in the relationship illustrated in Fig. 1, an operator mounts a holder H on each of the outwardly extending spindles 17 at the station indicated by the reference character A. The holders H are herein illustrated in the form of cylindrical perforated tubes

having annular flanges at their lower ends for co-operation with the annular seats on the nipples 74, the flanges being notched on the underside to cooperate with the notches in the rings 19. The holders, however, may take other forms than that herein illustrated or be supported on the turntable by other means than the spindles herein shown. When a holder H has been placed on each of the spindles 17 with its notched flange interlocking with the notched ring 19 surrounding the spindle the operator rotates the turntable 5 to transfer the holders to the station indicated by the reference character B by turning the crank 27 through one complete revolution. To this end the operator draws the handle 28 outwardly away from the stanchion 26 to withdraw the plunger-pin 29 from the recess 30 and then turns the crank 27, until the pin 29 automatically engages the recess 30 again to lock the turntable in position after the shaft 23 has been rotated through a complete revolution. The rotation of the shaft 23 acts through the pinion 22 and gear 20 to rotate the turntable 5 on the ball-bearing 14 surrounding the shaft 9. The holders H supported in a substantially horizontal plane at the station B are now loaded with groups of packages P by operators who apply the packages by sliding them over the ends of the holders while placing thin disk-like spacers S therebetween. Each package applied acts on the ones previously applied to force them inwardly on the holder H without damage to the yarn or deformation of the package. In this manner the operators may quickly and conveniently assemble the packages on the holders without fatigue.

When a group of packages P has been mounted on each of the holders H the turntable 5 is again rotated in the manner previously explained to transfer the groups of packages to the station indicated by the reference character C. At this station the end caps K are screwed onto the ends of the holders H to retain the packages in position thereon, thereby forming self-contained units of the groups of packages. Due to the interlocking engagement of the notched flanges 18 on the base of the holders H with the notched rings 19 surrounding the spindles 17, the holders are prevented from rotation while the caps K are screwed onto their ends. After caps K have been applied to all of the holders H the turntable is again rotated to transfer the package units to the station indicated by the reference character D; it being understood that during the rotation of the turntable with respect to the various stations the operators have continuously applied holders to the advanced spindles 17 at station A, mounted a group of packages on each holder at station B, and applied the caps K to the end of the holders at station C.

At the station D the assembled and self-contained package units are located opposite the opening 76 in the cover 62 to adapt them to be conveniently placed over the guides 75. The hinged platform 78 is placed across the opening 76 with the wheels or casters 79 resting upon the top of the carrier 70 as illustrated by full lines in Fig. 3. The operator standing on the platform 78 withdraws the assembled package units from the spindles 17 and lowers them directly onto the supporting guides 75 on the carrier 70 at one side of the platform with a substantially continuous motion. Due to the proximity of the carrier 70 to the assembled turntable 5 and the fact that the operator may stand directly over the carrier, the operation of transferring the assembled package

units is simplified and the time factor greatly reduced as compared with previously-used methods. When each of the supporting guides 75 on the carrier 70 adjacent one side of the platform 78 5 mounts a package unit the operator turns the handwheel 64 which acts through the shaft 60, gears 59, 61 and 53, pulley 52 and the belt 50 and sheave 51 to rotate the turntable 35 to thereby bring an empty portion of the carrier into position directly adjacent the side of the platform 78 10 as the empty guides pass therebeneath.

The above-described sequence of operations is 15 repeated until the first mounted package units on the carrier 70 have been carried around to a position adjacent the opposite side of the platform 78, at which time the platform is lifted in the manner indicated by the dash lines in Fig. 3 and swung back to inoperative position. Additional package units may then be mounted on the remaining empty guides 75 by reaching inwardly 20 from the side of the opening 76 and lowering them into place. When a complete batch of the package units has been mounted on the carrier 70 the loaded carrier is withdrawn from the pit 36 25 through the opening 76 and an empty carrier lowered into operative position on the turntable 35. It will be understood that the loaded carrier 70 is bodily lifted into a kier or other processing apparatus with the package units self-contained 30 thereon to adapt the yarn to be treated while supported on the holders H.

It will be observed from the foregoing that the present invention provides a novel method and apparatus for facilitating the assembly of groups 35 of packages on their holders and the mounting of the assembled package units in operative position for subsequent processing treatment. It will further be observed that the assembly turntable provides for a division of labor in the assembling 40 operation which materially reduces the time factor and increases the efficiency of the operators with less physical effort and fatigue on their part. It will also be observed that the construction and arrangement of the turntables with respect to 45 each other coordinates the assembly of the packages and the mounting of the package units and provides a simple form of apparatus requiring little or no skill to operate.

While I have herein described and illustrated 50 the present apparatus as embodied in a preferred form of construction, by way of example, it is to be understood that various modifications may be made therein without departing from the spirit or scope of the invention. Therefore, without 55 limiting myself in this respect, I claim:

1. The method of assembling groups of textile packages which comprises mounting package-holders for movement about a central axis from one to another of a plurality of stations, applying 60 a group of packages to each holder in tandem by sliding them over the end thereof at one station, securing the packages on the holders, and removing the holders with the packages assembled thereon at another station.

2. The method of preparing textile packages for 65 subsequent processing treatment which comprises mounting package-holders for movement to a plurality of stations, applying a group of packages to each holder in tandem at one station by sliding them over the end thereof, securing the packages 70 on the holders at another station, and removing the holders with the groups of packages assembled thereon at another station.

3. The method of assembling textile packages 75 in self-contained units on holders and mounting

the units on carriers for subsequent treatment in a processing apparatus which comprises moving the holders through a predetermined path to a plurality of stations, assembling a group of packages in tandem on each of the holders and fastening them in place thereon at a plurality of the stations, transferring the assembled package units to a carrier at a transfer station, and intermittently moving the carrier in a predetermined path adjacent the transfer station. 10

4. The method of assembling groups of packages on holders to form self-contained units and mounting the units on a carrier for subsequent treatment in a processing apparatus which comprises moving the holders to a plurality of stations in a closed course, simultaneously moving the carrier to position different portions thereof adjacent to and below one of the stations in the path of the holders, assembling a group of packages on each holder and fastening them in place 15 thereon at a plurality of the stations, and transferring the assembled package units to the carrier when positioned adjacent thereto. 20

5. An apparatus for assembling textile packages for subsequent processing treatment comprising a turntable provided with means on which groups of packages may be assembled in tandem to form self-contained units, a carrier having means for mounting a plurality of the package units, and a turntable for rotatably supporting the carrier 25 adjacent the assembly turntable to provide for transferring the package units from the assembly turntable to the carrier. 30

6. An apparatus for assembling textile packages for subsequent processing treatment comprising a turntable having means on which groups of packages may be assembled in tandem to form self-contained units, a second turntable mounted below said assembly turntable, a carrier on said second turntable provided with supporting means 40 for mounting a plurality of package units, means for rotating the assembly turntable to position the assembled package units adjacent the carrier, and means for rotating the carrier-supporting turntable to position its unit-supporting 45 means adjacent the assembly turntable. 50

7. An apparatus for assembling textile packages in hollow holders for subsequent processing treatment comprising a turntable provided with means for supporting the holders on which groups of packages are assembled in tandem to form self-contained units, a second turntable mounted below said first turntable, a carrier supported on said second turntable and having supporting means for mounting a plurality of package units, a platform overlying one side of the second turntable above its unit-supporting means, and means for rotating the carrier-supporting turntable to position different groups of the supporting means on the carrier at the side of the platform in convenient position to mount the package units removed from the first turntable. 55

8. In an apparatus for assembling groups of textile packages on holders to form self-contained units, a pedestal, a turntable rotatably mounted on the pedestal, means on the turntable for supporting package holders, means for rotating the turntable to a plurality of stations, and means for locking the turntable in position at each of the stations. 60

9. In an apparatus for assembling groups of textile packages on hollow perforated holders to form self-contained units, a turntable, means for mounting the holders on the turntable, a gear on the turntable, a pinion cooperating with the 70 75

gear to rotate the turntable to transfer groups of the holders from one station to another during one revolution, a crank for rotating the pinion, and automatically-operated means for locking the crank at the completion of each revolution.

5 10. An apparatus for assembling a batch of package units comprising a turntable, a portable carrier detachably mounted on the turntable, means on the carrier for detachably supporting 10 a plurality of package units, and means for rotating the turntable.

11. An apparatus for assembling a batch of package units comprising a turntable, a hollow portable carrier detachably mounted on the turntable, means on the carrier for detachably supporting a plurality of packages assembled on 15 holders, gearing for rotating the turntable, and a manually-rotatable shaft for actuating the gearing to rotate the turntable.

20 12. In combination, a pair of turntables, means on one of said turntables for detachably supporting radially-extending package-holders, means on the other turntable for supporting the package-holders in vertical arrangement, and 25 means to rotate the turntables to carry groups

of loaded package-holders into position to be transferred to the supporting means on the second turntable.

13. In combination, a turntable having means for supporting a plurality of package-holders extending radially from its axis, a second turntable, a carrier on the second turntable having means for supporting the package-holders in vertical arrangement, and means to rotate the turntables to locate the groups of the loaded 10 package-holders adjacent the second turntable and in position to be transferred to the carrier.

14. In combination, a turntable provided with means for supporting a plurality of package-holders projecting radially therefrom, a second 15 turntable arranged at a level below the first turntable with its periphery adjacent the periphery of the first turntable at one point, a carrier on the second turntable having means for supporting the package-holders in vertical arrangement, and means to rotate the turntables to locate groups of the loaded package-holders in position to be transferred from the first turntable to the carrier on the second turntable.

ROYAL LITTLE. 25
